UNITED STATES PATENT OFFICE.

JOHN KNAPE, OF GRAND RAPIDS, MICHIGAN.

ADJUSTABLE BRACKET.

941,682.

Specification of Letters Patent. Patented Nov. 30, 1909.

Application filed February 9, 1909. Serial No. 476,900.

To all whom it may concern:

Be it known that I, JOHN KNAPE, a citizen of the United States of America, residing at Grand Rapids, in the county of Kent and State of Michigan, have invented certain new and useful Improvements in Adjustable Brackets; and I do hereby declare the following to be a full, clear, and exact description of the invention, such as will enable others skilled in the art to which it appertains to make and use the same.

My invention relates to improvements in adjustable brackets, and its object is to provide the same with improved interlocking means to hold the bracket securely and rigidly, and to provide the device with various new and useful features, hereinafter more fully described and particularly pointed out in the claims, reference being had to the accompanying drawings, in which:

Figure 1 is a perspective of a device embodying my invention; Fig. 2 a detail in side elevation, and with parts broken away to show the construction; Fig. 3 a front elevation of the channel bar with the fastening means in section in the plane of the face of the bar; Fig. 4 a vertical section of the arm on the line 4—4 of Fig. 2; Fig. 5 an enlarged detail in horizontal section on the line 5—5 of Fig. 2; and, Fig. 6 a detail of a portion of the device in side elevation.

Like numbers refer to like parts in all of the figures.

1 represents a channel bar adapted to be secured to any suitable support and provided with keyhole slots 2 with the lateral opening thereof having converging sides as at 2^a.

3 is an arm preferably of sheet metal arranged in a vertical plane and having an opening 4 near the upper corner adjacent to the channel bar, and a slot 4^a extending from said opening to receive a bolt 7.

5 are side strips secured to the end of the arm 3 adjacent the channel bar 1, the edges 45 of said side strips together with the end of the arm being in the same plane and forming an end surface adapted to rest firmly against the face of the channel bar. These side strips are swaged outward in opposite directions as at 6 to fit the neck 9 of the bolt, which neck is wedge shaped in cross section, whereby it fits firmly between the converging walls of the portion 2^a of the keyhole slots, and can not be inserted in the arm in 50 any other than the proper position, with the narrow side downward and the head of the

bolt adapted to pass through the upper or circular portion of the keyhole slot. Opposite the lower ends of the side strips 5 are hooks 10 integral with said strips and 60 adapted to enter the keyhole slots, and also provided with inclined forward surfaces opposite the lower corners of the strips 5, and oppositely inclined side surfaces 11 to fit between the converging sides 2^a of the keyhole 65 slots. The bolt 7 is provided preferably with a suitable nut 8, whereby the head thereof is drawn tightly against the inner surface of the hook 10 and the clamping action 70 of the bolt 9, thus firmly hold the end of the arm and the edges of the strips 5 against the face of the channel bar, and the wedge shaped neck 9 and inclined surfaces 11 of the hooks firmly wedged between the converging sides 2^a prevent all lateral movement 75 of the arm.

By loosening the bolt 7 the device may be readily detached and adjusted in various keyhole slots, which are spaced apart a suitable distance for such adjustment.

Obviously the arm may be made of a cast structure with the side strips 5 and hooks 10 integral therewith without departing from my invention.

What I claim is:—

1. An adjustable bracket, comprising a channel bar provided with keyhole slots having downwardly converging sides, an arm having an opening near the upper corner, a bolt extending into said opening and projecting from the arm, said bolt also having a neck wedge-shaped in cross section to engage the converging sides of a slot, and a hook near the lower part of the arm having converging sides to fit the converging sides of a slot.

2. An adjustable bracket, comprising a channel bar having keyhole slots, an arm consisting of a plate having an opening 100 near its upper corner and a slot extending from said opening to receive a bolt, side strips secured to said arm and swaged opposite said slot to receive the bolt, hooks on said strips opposite the lower corner of 105 said arm, and a bolt in said arm projecting within said opening and provided with a nut also within the opening.

3. An adjustable bracket, comprising a channel bar having a series of keyhole slots 110 provided with downwardly converging sides, an arm having an opening near its

upper corner and a slot extending from said opening to receive the bolt, a bolt having a neck wedge-shaped in cross section inserted in the arm and having a nut within 5 said opening, side strips formed to fit the wedge-shaped neck of the bolt and secured to the end of the arm, and hooks on the side strips opposite the lower corner of the arm having inclined opposite sides to engage 10 the converging sides of a keyhole slot.

4. An adjustable bracket, comprising a channel bar having a series of keyhole slots with downwardly converging sides, an arm having a flat end adapted to adjustably 15 engage the face of the channel bar and also having an opening near its upper corner and a slot extending from said opening to re-

ceive the bolt, a bolt in said slot having a neck wedge-shaped in cross section and a nut within said opening, strips secured to 20 the arm and swaged to fit the neck of the bolt and embrace the same, and hooks on said strips near the lower corner of the arm, said hooks being inclined at the side toward the arm and also inclined at opposite sides 25 to engage the converging sides of a keyhole slot.

In testimony whereof I affix my signature in presence of two witnesses.

JOHN KNAPE.
